(57) **CLAIM**

The ornamental design for a toy laser gun set, as shown and described.

DESCRIPTION

FIG. 1 is a first perspective view of a first element of a toy laser gun set showing my new design;

FIG. 2 is a second perspective view of the first element thereof;

FIG. 3 is a front view of the first element thereof;

FIG. 4 is a back view of the first element thereof;

FIG. 5 is a left side view of the first element thereof;

FIG. 6 is a right side view of the first element thereof;

FIG. 7 is a top view of the first element thereof;

FIG. 8 is a bottom view of the first element thereof;

FIG. 9 is a first perspective view of a second element of a toy laser gun set showing my new design;

FIG. 10 is a second perspective view of the second element thereof;

FIG. 11 is a front view of the second element thereof;

FIG. 12 is a back view of the second element thereof;

FIG. 13 is a left side view of the second element thereof;

FIG. 14 is a right side view of the second element thereof;

FIG. 15 is a top view of the second element thereof;

FIG. 16 is a bottom view of the second element thereof;

FIG. 17 is a combination view of the first element and the second element of the toy laser gun set thereof;

FIG. 18 is an enlarged view of area “18” in FIG. 1;

FIG. 19 is an enlarged view of area “19” in FIG. 2; and,

FIG. 20 is an enlarged view of area “20” in FIG. 9.

The evenly broken lines shown in the drawings depict portions of the toy laser gun set that form no part of the claimed design. The dash-dot broken lines shown in FIGS. 1-2, 9, and 18-20 are for the purpose of indicating the enlarged partial views and form no part of the claimed design.

1 Claim, 20 Drawing Sheets
